UNITED STATES PATENT OFFICE.

WILLY G. SESSER, OF DETROIT, MICHIGAN, ASSIGNOR TO GREATER DETROIT REXALL CLUB, OF DETROIT, MICHIGAN, A VOLUNTARY ASSOCIATION.

DESIGN FOR A SIGN.

Application filed March 29, 1923. Serial No. 5,644. Term of patent 14 years.

To all whom it may concern:

Be it known that I, WILLY G. SESSER, a citizen of the United States, residing at Detroit, in the county of Wayne and State of Michigan, have invented a new, original, and ornamental Design for Signs, of which the following is a specification, reference being had to the accompanying drawing, forming part thereof.

Fig. 1 is a front elevation of a sign, showing my new design; and Fig. 2 is an edge elevation thereof.

I claim:

The ornamental design for a sign, as shown.

WILLY G. SESSER.
